US0D1032416S

(12) **United States Design Patent** (10) Patent No.: **US D1,032,416 S**
(45) Date of Patent: ** Jun. 25, 2024

(54) **ELECTRIC MOTORCYCLE**

(71) Applicant: **Ningbo Engineering Technology Co., Ltd**, Zhejiang (CN)

(72) Inventors: **Fang Zhang**, Zhejiang (CN); **Yirui Jin**, Zhejiang (CN); **Shanqing Jiang**, Zhejiang (CN)

(73) Assignee: **Ningbo Engineering Technology Co., Ltd**, Ningbo (CN)

(**) Term: **15 Years**

(21) Appl. No.: **29/909,763**

(22) Filed: **Aug. 10, 2023**

(30) **Foreign Application Priority Data**

Jul. 20, 2023 (CN) 202330456053.4

(57) **CLAIM**

The ornamental design for an electric motorcycle, as shown and described.

DESCRIPTION

FIG. 1 is a rear, left side perspective view of an electric motorcycle, showing my new design;

FIG. 2 is a second perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof; and,

FIG. 8 is a bottom plan view thereof;

FIG. 9 is a perspective view of another state of the electric motorcycle thereof; and,

FIG. 10 is a perspective view of another state of the electric motorcycle thereof.

1 Claim, 10 Drawing Sheets
